UNITED STATES PATENT OFFICE.

MARIO SCHIESARI, OF TURIN, ITALY.

TYPE-WRITING MACHINE.

1,035,814.

Specification of Letters Patent. Patented Aug. 13, 1912.

Original application filed October 4, 1905, Serial No. 281,326. Divided and this application filed March 8, 1910. Serial No. 547,954.

To all whom it may concern:

Be it known that I, MARIO SCHIESARI, a subject of the King of Italy, residing in Turin, Italy, have invented certain Improvements in Type-Writing Machines, of which the following is a specification.

This invention relates to new and useful improvements in typewriters and has relation more particularly to the carriage feed mechanism therefor, the device herein described being a division of the application filed October 4, 1905, Serial No. 281,326.

The object of the invention is to provide a novel device for feeding the paper proportionately to the characters printed thereon.

In describing the invention in detail, reference will be had to the accompanying drawings forming a part of this specification, wherein like characters of reference denote corresponding parts, in the several views and in which—

Figure 1 is a plan of the machine illustrating the carriage feeding mechanism, the upper part of the carriage being omitted; Fig. 2 is a vertical sectional view; Fig. 3 is an elevation of the rear or back part of the machine; Fig. 4 is a perspective view of the rear part of the machine showing the mechanism in inoperative position; and Fig. 5 is the same view showing the mechanism in operative position.

In the drawings, 4 denotes a key lever provided with a key 1 which, through its component parts, is intended to depress a type lever or hammer 13. The said hammer 13 is fulcrumed on a pivot 24 carried by an arm 20 on a suspension bar 16 suspended from the upper part 19 of the frame of the machine by a screw 18 in such a manner that it may oscillate laterally. This suspension bar 16 carries at its lower part a spacer 15 and a small roller 21 on which bears the spacer of the adjacent bar.

On depressing a key, and consequently the intermediate lever 7, the spacer link 14 is drawn down and this rocks the spacer cam 15 in a manner to cause it to act on the adjacent roller 21 and move laterally the suspension bar 16 on which said roller is mounted. Evidently this will displace all of the bars successive to that which has been displaced by the key, and also the last suspension bar 35.

The movement of the carriage which car-

ries the paper ought obviously, to be proportional to the number of keys depressed. The power required for moving the carriage is supplied by a spring inclosed within a casing or drum 52 (Fig. 3) which may be wound up by turning the arbor 56 which acts to wind the spring through the bevel wheels 54 and 55, and which is rotated either by means of a key 58, or by means of a pedal acting through a cord wound about a drum 57 ratcheted on the arbor 56.

The drum 52 (Fig. 2) is in one piece with a gear wheel 53, which gears with a wheel 59, fixed on an arbor 60 and this arbor transmits with motion to the upper wheel 61, which latter gears with the rack 45 solid with the carriage. In order to render the movement of the carriage always proportional to the number of type keys that may be simultaneously pressed, there is an arbor 39 (Fig. 1) journaled at 40 and 41, which has an arm 42, that is designed to raise or lift up a detent 43 (Fig. 1) and a special detent 44 pivoted to the detent 43 and capable of movement laterally thereof. On the said arbor 39 are also two arms 46 through which the vertical movement of a transverse bar 47 which has springs 48 that keep it always pressed against the lever 7, gives place to the rotation of the arbor 39. From this it follows, that when the type keys are pressed down, and with them the levers 7, this obliges the detents 43 and 44 to turn in a vertical plane and the detent 44 will free itself from the teeth of the outer rack 45 the moment after the detent 43 shall have engaged them. This detent 43 being fixed against lateral play, prevents the rack and carriage from displacement, while the detent 44, being free, will allow a lateral displacement equal to that of the last suspension bar 35, that is to say to an extent equal to the sum of all the displacements caused by the spacers for example, two teeth as shown in Fig. 5. This displacement of the bar is allowed to the detent 44 by levers 51 and 50, against which a spring 49 presses the said detent 44.

When the pressure is removed from the type keys, the spring returns to its position the transverse bar 47, and in consequence the first detent 43 is disengaged from the rack a moment after the special detent 44 is engaged anew therewith.

When the syllable written is the last one

2
of a word, it would suffice, in order to separate it from the word that is to follow, to depress a key which is not provided with a type-hammer.

5. I claim:

1. A device of the character described comprising suspension bars capable of movement, the last of which receives a displacement equal to the sum of displacements of all the bars, a carriage, a rack on the carriage, means acting in conjunction with the rack capable of operation to hold the carriage against movement, and means engageable with the rack when the locking means is inoperative, and capable of operation to permit a displacement of the carriage equal to the displacement of the last extension bar.
2. Type writing machine in which more keys may be simultaneously depressed in order to write syllables, comprising in combination suspension bars capable of being swung laterally, the last of which receives a displacement equal to the sum of displacements of all the bars, a carriage, a rack on the carriage, means for moving the carriage in one direction, a detent movable laterally, the position of which is controlled by the last suspension bar, a fixed detent for stopping the carriage and a device for engaging the fixed detent and disengaging the movable one when the impression of the characters is effected.
3. A device of the character described comprising suspension bars capable of swinging movement, the last of which receives a displacement equal to the sum of displacements of all the bars, a carriage, a rack on the carriage, means for moving the carriage in one direction, and a stop device for the carriage controlled by the last suspension bar and caused to engage with said rack

when the pressure is removed from the suspension bars.

4. A device of the character described comprising suspension bars capable of movement, the last of which receives a displacement equal to the sum of displacements of all the bars, a carriage, means for moving the carriage in one direction, and a stop device for the carriage controlled by the last suspension bar and caused to engage with said carriage when pressure is removed from said suspension bars.

5. A device of the character described comprising suspension bars capable of lateral movement, the last of which receives a displacement equal to the sum of displacements of all the bars, a carriage, means for imparting movement to the carriage and means controlled by the last suspension bar for holding the carriage against movement.

6. A device of the character described comprising suspension bars capable of movement, the last of which receives a displacement equal to the sum of displacements of all the bars, a carriage, means for moving the carriage in one direction, a stop device for the carriage controlled by the last suspension bar, and caused to engage with said carriage when pressure is removed from said suspension bar and an auxiliary stop device operative when the first stop device is inoperative and capable of operation to permit displacement of the carriage upon each movement of the suspension bar.

In testimony whereof I have hereunto signed my name in the presence of two subscribing witnesses.

MARIO SCHIESARI.
